UNITED STATES PATENT OFFICE.

MILTON O. SARGENT, OF MALDEN, MASSACHUSETTS, ASSIGNOR OF THREE-FOURTHS TO JAMES N. GEORGE, OF PLAISTOW, NEW HAMPSHIRE, CHARLES A. STEARNS, OF WATERTOWN, AND CHARLES L. BLY, OF BRADFORD, MASSACHUSETTS.

ELECTRIC-CURRENT CONTROLLER.

SPECIFICATION forming part of Letters Patent No. 433,744, dated August 5, 1890.

Application filed May 20, 1890. Serial No. 352,469. (No model.)

To all whom it may concern:

Be it known that I, MILTON O. SARGENT, residing at Malden, in the county of Middlesex and State of Massachusetts, have invented 5 certain Improvements in Electric-Current Controllers, of which the following is a specification.

This invention relates to electric-current controllers and to a device which is operated 10 by the heat generated in the core of a coil of wire which forms a part of and is interposed in the circuit or circuits which are to be changed, regulated, or controlled, the heat in the core being the result of the passage of 15 currents of electricity through the same, the coil and its core constituting a current-controller.

My invention also relates to the application 20 of such a device in combination with electrical circuits and instruments.

I have shown my invention applied to the protection of electrical instruments from the abnormal or strong currents of electricity which are liable to traverse the wires of circuits arranged for low-intensity currents by 25 reason of leakages from or crosses with wires carrying such abnormal or high-intensity currents and by reason of dangerous earth-currents also.

30 The ordinary method of protection from abnormal currents is to place between the line and the instruments to be protected a fusible wire, which is relied upon to fuse or blow out where such foreign currents come 35 onto the line, or to place therein a magneto-electric apparatus for shunting the instruments either by opening the line or by putting on a ground to convey the foreign current to the earth. It has been found that 40 while these devices are well enough for cases where powerful currents are used in the circuits to be protected, they are not efficient in circuits using currents of comparatively low intensity. The real danger to low-tension 45 circuit instruments arises from what are denominated "sneak currents," or those currents which can be safely carried by and past

the fusible wire and which heat the fine wires of the instrument-coils and destroy them before the fusible wire is fused or "blown." 50

In carrying out my invention I employ a fusible wire between the line and the instruments to be protected, as in the ordinary way, and in addition thereto insert between the fusible wire and the instruments a device 55 which stops all currents, including the sneak currents, which are of higher intensity or greater volume than those for which the line and instruments are arranged to carry and to be operated by, all of which I will now proceed to describe, and point out in the claims. 60

In the accompanying drawings, Figure 1 shows a line terminal embodying my invention, and Fig. 2 is a diagram showing my method of protecting the instruments at an 65 intermediate station on a circuit. Fig. 3 is an enlarged view, and Fig. 4 a cross-section on line xx thereof, of the circuit-controller shown in Fig. 1. Fig. 5 is an enlarged view 70 of a modification of the circuit-controller.

Referring to Fig. 1, w is the line-wire entering a terminal station at post 5, between which and post 6 is a fusible wire f . From the post 6 the circuit extends to post 2, projecting from the side of a box A, made of insulating material. The box A contains an arrangement of my improved circuit-changer, regulator, or controller. The post 2 extends through the wall and into the interior of the box. At its inner end is pivoted a metal lever b , at c , whose free end has upon its upper side a contact-pin d . Directly over the pin d is a contact e , (preferably of carbon, to avoid the "sticking" occasioned by two metal contacts coming together,) on the inner end of the 85 post 4, which projects from the top of the box. The contacts d and e are normally separated or open. A wire w' extends to the earth G . The free end of the lever b rests upon the upper surface and end of a curved 90 flat metal tube a , whose opposite end is secured to the post 3 by the screw f' . This flat tube is partly filled with alcohol or ether and is hermetically sealed. Around the lower

portion of the tube is wound a coil *c* of fine insulated wire, (usually of about the size of the wire forming the helices or coils in the instruments to be protected,) one end of which 5 extends to and is secured to the inner end *g* of the post 2, and the other end extends to and is secured to the inner end of post 1, which projects from the side of the box. A wire *w'* extends from the post 7 to the instrument I to be protected, from which a wire goes to ground *G*. The metal tube *a* forms the core of the fine-wire coil *c*, which normally forms a portion of (and of higher resistance than) the main-line circuit. Figs. 3 and 10 15 show, enlarged, the circuit-controller as composed of a coil of wire *c*, and a central core *a* in the form of a flat tube, which is partially filled, as hereinbefore described, with alcohol, ether, or other such fluid.

20 The operation of the device is as follows: The ordinary currents of electricity to operate the instrument I enter by wire *w*, fuse *f*, post 2, wire *w'* to coil *c*, thence to post 7 by wire *w'* to instrument I and ground *G*. If 25 by reason of leakage or a wire-cross a very heavy current comes in by wire *w*, the fusible wire *f* is fused or blown out, and the circuit being opened the foreign current cannot reach the instrument I; but if a sneak current comes in by wire *w* which can be carried by the fusible wire *f* without fusing it, it passes by the wire *w'* through the convolutions of the core *c*, which, being of smaller diameter than the line- or fusible wire, presents 30 a resistance to the passage of the sneak current sufficient to heat the hollow metal core *a*, causing the inclosed liquid to expand. In so doing the free curved end of the tube tends to straighten out, and thereby lifts the 35 lever *b* and forces its contact-pin *d* into contact with the contact *e*, thus furnishing a shunt-circuit of lower resistance for the foreign current to earth *G* by way of line *w*, post 2, substance of lever *b*, contacts *d* and *e*, 40 post 4, wire *w'* to earth *G'*, and if the sneak current continues the fusible wire *f* fuses and opens the circuit; but if the sneak current ceases before the fusible wire is fused 45 the core-tube *a* cools down and resumes its 50 normal shape, allowing the lever to drop and open the shunt-circuit, the instrument-circuit being thus automatically restored.

Instead of the pivoted lever *b*, I may use any equivalent contact-maker—as, for instance, a metal spring attached by one end to the post *g*.

Fig. 2 shows a modification of my invention arranged at an intermediate station on a circuit. At terminal stations, as shown 60 in Fig. 1, the danger from high-tension or abnormal currents to a low-tension circuit is from one direction only—the line-entering side—but at intermediate stations the danger is from two directions or sources, i. e., the entering and departing line-wires.

In Fig. 2 the line-wire *w* passes to post 5,

between which and post 6 is a fusible wire *f*. The line continues by wire *w'*, coil *c*, wire *w'*, to instrument I to be protected, thence by wire *w'* to post 12, between which and post 70 13 is a fusible wire *f'*, the line extending outward to the next station by wire *w''*.

Resting upon the curved upper part of the core-tube *a* is the pivoted lever *b*. Near its pivot is a contact *h*, directly over which and 75 normally separated therefrom is a spring *s*, connected to ground by wire 14. At its outer end are two contact-pins *i* and *j*. Directly over each pin are springs 8 and 9, insulated from each other by block 10. A wire 7 extends from post 6 to spring 8, and also a wire 11 extends from post to spring 9.

The ordinary working-current of instrument I may enter from either side, keeping on wire *w* *w'* *w''*, passing through fuses *f* *f'* 85 and coils *I* and *e* without disturbing the adjustment of the circuit; but suppose a sneak current to enter from the right side in the direction of the arrow, if it passes the fuse *f* it heats the core *a* of the coil *c*, causing it to straighten and close the contact *h* with spring *s*, and goes to ground at *G* by way of wire 7, spring 8, lever *b*, spring *s*, and wire 14, and maybe blows out the fuse *f*. If a sneak current comes in from the left side 90 in the direction of the dotted arrow it passes the fuse *f'* through coils *I* to coil *c*, heating its core *a* and thereby closing the contacts *j* with 9 and *i* with 8, shunting the current by wire 11, lever *b*, and wire 14 to ground, and 100 possibly fusing the wire *f'*. In this example, although the sneak current passes through the coils *I* of the instrument, the core of coil *c* is so sensitive that a shunt is made thereby before the instrument-coils are injured.

I do not limit myself to the described thermostatic core *a*, as I may use one composed of two differentially-expansible metals, as in Fig. 5, where the core of the coil is shown as constructed, the form of the core being the same as shown in Fig. 2. To obtain the heating effect the wire of the coil need not vary much in size from the ordinary office-wire used for making connections, as the convolutions of the coil create sufficient resistance to produce the heat. This is, however, a matter of adjustment.

In some cases it is desirable, when the lever *b* has been pushed up by the expansion of the core *a* and closed the contacts *d* and *e*, shunting the foreign currents to ground, to maintain the ground-connection. To effect this result I provide means, as indicated in dotted lines in Fig. 1, to lock the bar or lever *b* when raised. *l* is a projection from the under side 125 of the free end of the lever *b*, and *m* is a spring attached to the inside of the box *A*, having its free end in the path of the projection *l*, and when the lever *b* is raised the projection presses the spring back. As it passes 130 it, the spring returns to its normal position and prevents the lever from falling down and

opening the circuit, thus maintaining the shunt or ground circuit until manually broken.

I claim—

- 5 1. The combination of an electric-current-controlling device consisting of a coil of wire having a central metallic tubular core, partially filled with fluid, as described, one end of which is secured to a support while its other end is free and curved, the said coil being normally in a main circuit, and a normally-open grounded branch circuit adapted to be closed by means of said core.
- 10 2. The combination, in an electric circuit, of a main line, a fusible wire, a current-controlling device consisting of a coil of wire forming a part of said main line, having a central metallic tubular core, partially filled with fluid, as described, one end of said core being secured to a support while its other end is free and curved, electrical instruments in the said main line having a ground-wire, and a normally-open grounded branch circuit.
- 15 25 3. An electric-current-controlling device consisting of a coil of wire having a central metallic tubular core partially filled with fluid, as described, one end of which is se-

cured to a support while its other end is free and curved, the said coil being normally in a main circuit, and a normally-open grounded branch circuit consisting of a contact-lever and a grounded wire, one end of said lever being pivoted to a support in electrical connection with the said main circuit, its other end resting by gravity upon the free and curved end of said core and adapted to make electrical contact with said grounded wire.

4. In an electric circuit, the combination of two fusible plugs, electrical instruments, a current-regulating device consisting of a coil having a thermostatic contact-regulating core, and two shunt-circuits composed of a normally-open contact-maker, and a ground-wire common to both shunt-circuits, and two shunt-circuit wires, as 7 and 11, as and for the purposes set forth.

In testimony whereof I have signed my name to this specification, in the presence of two subscribing witnesses, this 19th day of May, A. D. 1890.

MILTON O. SARGENT.
